UNITED STATES PATENT OFFICE.

JAMES PURCELL, OF WINONA, NORTH DAKOTA.

BRIDLE-BIT.

SPECIFICATION forming part of Letters Patent No. 660,923, dated October 30, 1900.

Application filed April 9, 1900. Serial No. 12,211. (No model.)

To all whom it may concern:

Be it known that I, JAMES PURCELL, a citizen of the United States, residing at Winona, in the county of Emmons and State of North Dakota, have invented certain new and useful Improvements in Bridle-Bits; and I do hereby declare the following to be a full, clear, and exact description of the invention, such as will enable others skilled in the art to which it appertains to make and use the same.

My invention relates to improvements in bridle-bits, and particularly to that class of bridle-bits known as "curb-bits."

My invention is intended to produce a bit which may possess the qualities of both a straight or easy bit and a curb-bit.

My invention will be understood by reference to the accompanying drawings, wherein the same parts are indicated by the same letters throughout the several views.

Figure 1 represents a perspective view of a portion of a bit embodying my invention, but one side bar being shown and parts being broken away to more clearly illustrate the interior construction. Fig. 2 is a front elevation of the parts shown in Fig. 1. Fig. 3 is a section taken on line 33 in Fig. 1 looking in the direction of the arrow; and Fig. 4 is a front elevation of the bit complete, the same being shown on a much smaller scale than the other figures of the drawings.

A represents one of the side bars of the bit, this side bar being provided at its upper end with a loop or ring A⁰ for the reception of the cheek-straps A² and the curb-chain A³ and having a depending extension A' below the bit-bar B, the said extension A' being set at the slight angle backward from the general line of the side bar A, as will be seen in Fig. 1. The said extension A' has at its lower end a curved hook a', extending toward the front of the bar. The lower ends of the extensions A' may, if desired, be connected by means of a cross-rod b, for stiffening and strengthening the same; but this cross-bar is not essential. Upon the forward side of the bar A is formed or fixed a hollow cylinder C. Within this cylinder is located a coil-spring C⁰, held under tension therein, said spring being seated at the lower end c of the cylinder and being movable at its upper end c', and being retained within the upper portion of the cylinder by means of a cap c⁰,

screwed onto or otherwise retained upon the upper end of the said cylinder, as also seen in Fig. 1. A chain D passes through the cylinder C and through the said coil-spring C⁰ therein, said chain being attached at its upper end to a button or follower d, which fits closely, but easily, within the said cylinder, and against which the upper end c' of the coil-spring C⁰ bears. The lower end of the chain D extends through the lower end of the cylinder, which is open and is connected to a sliding lock E, having a groove e (seen in Fig. 3) upon its rear face for engaging with the forward edge of the inclined extension A', along which said block slides accordingly as the chain is drawn out or retracted under the influence of the rein or the spring C⁰. To this sliding block E is pivotally connected a link F, carrying a ring F⁰ for the reception of one end of the bridle-rein F². This link F has an opening f therethrough which incloses the extension A' of the side bar of the bit and serves as a guide for the sliding block E. The extension A' preferably tapers from its upper end, which is approximately at the lower end of the cylinder, toward its lower end, its width from front to rear at its upper end being sufficient to fit closely within the link F 80 and prevent undue rattling of the parts.

The sliding block E has a circular plate or disk E' upon its upper side, and upon this circular plate or disk E' is secured a disk or washer E², of some soft material, such as leather or rubber, said disk or washer E² constituting a gasket which closes securely the lower end of the cylinder C against the entry of moisture, grit, or other foreign substances that would be likely to injure the spring when the chain is retracted.

The operation of the device is as follows: When in its normal position—that is to say, when there is no excessive strain upon the reins of the bridle—the chain D is retained almost or quite entirely within the cylinder, and the sliding block E and the link F, pivoted thereto, are held in a position near to the mouth-bar B. In this position the leverage upon the mouth-bar B is small and the effect of the bit on the horse's mouth is mild; but as the pull upon the reins increases the sliding block and chain will be drawn downwardly in proportion to the degree of excess-

ive pull required, and as the said sliding block, carrying with it the pivoted link F, moves downwardly along the extension A' of the cheek-bar A the leverage upon the mouth-bar B is increased. In this manner the severity of the bit adjusts itself automatically as occasion requires in controlling the animal.

The hooked end a' of the extension A' will arrest the downward movement of the link F and the sliding block E when these reach their downward limit and will prevent their being pulled over the end of the said extension and displaced.

Having thus described my invention, what I claim, and desire to secure by Letters Patent of the United States, is—

1. In a bridle-bit, the combination of the mouth-bar and side bars rigidly connected thereto, said side bars extending toward opposite sides of the said mouth-bar, a hollow cylinder fixed along the upper portion of each side bar, and coil-springs inclosed within said cylinders, links inclosing the lower extensions of said side bars, said links being provided with connections for the reins, a follower within the upper portion of each of said cylinders and flexible connections between the said links and the said followers, the said springs acting normally to elevate said links, substantially as described.
2. In a bridle-bit, the combination of the mouth-bar and side bars rigidly connected thereto, said side bars extending toward opposite sides of the said mouth-bar, a hollow cylinder fixed along the upper portion of each side bar, and coil-springs inclosed within said cylinders, links inclosing the lower extensions of said side bars, said links being provided with connections for the reins, a follower within the upper portion of each of said cylinders and flexible connections between the said links and the said followers the said springs acting normally to elevate said links, a removable cap closing the upper end of each of

said cylinders and a yielding disk carried by 45 said flexible connection arranged to close the lower end of each of said cylinders, substantially as described.

3. In a bridle-bit, the combination with the mouth-bar and side bars rigidly connected to 50 the ends thereof, said side bars extending toward opposite sides of said mouth-bar and inclined rearwardly at the lower ends; closed cylinders carried upon the upper portions of said side bars and coil-springs mounted under tension in said cylinders; of links inclosing the lower extensions of said side bars and movable therealong, followers within said cylinders, chains connected to the said followers within the upper portions of said cylinders; sliding blocks connected to said chains outside said cylinders, and pivotally connected to the said links, substantially as described.

4. In a bridle-bit, the combination with the 65 mouth-bar and side bars rigidly connected to the ends thereof, said side bars extending toward opposite sides of said mouth-bar and inclined rearwardly at the lower ends; closed cylinders carried upon the upper portions of 70 said side bars and coil-springs mounted under tension in said cylinders; of links inclosing the lower extensions of said side bars and movable therealong, followers within said cylinders, chains connected to the said followers within the upper portions of said cylinders: sliding blocks connected to said chains outside said cylinders and pivotally connected to the said links, means for closing the ends of said cylinders against the entry 80 of moisture or other foreign matter, substantially as described.

In testimony whereof I affix my signature in presence of two witnesses.

JAMES PURCELL.
